(57) **CLAIM**

We claim the ornamental design for a battery, as shown and described.

DESCRIPTION

FIG. 1 is a front perspective view of a battery showing the new design;

FIG. 2 is a rear perspective view of the battery shown in FIG. 1;

FIG. 3 is a front view of the battery shown in FIG. 1;

FIG. 4 is a rear view of the battery shown in FIG. 1;

FIG. 5 is a right side view of the battery shown in FIG. 1;

FIG. 6 is a left side view of the battery shown in FIG. 1;

FIG. 7 is a top plan view of the battery shown in FIG. 1; and,

FIG. 8 is a bottom plan view of the battery shown in FIG. 1.

The broken lines are shown for the purpose of illustrating parts of the article that form no part of the claimed design.

1 Claim, 6 Drawing Sheets
